UNITED STATES PATENT OFFICE.

STEPHEN CONDON, OF SPENCER, IOWA.

CLAMP FOR LEVELS.

Application filed May 20, 1922. Serial No. 562,461.

To all whom it may concern:

Be it known that I, STEPHEN CONDON, a citizen of the United States, and a resident of Spencer, in the county of Clay and State of Iowa, have invented certain new and useful Improvements in Clamps for Levels, of which the following is a specification.

My invention has for its object the production of a simple and improved means for removably securing a level to a straight edge which obviates the necessity of the workman holding the level against the straight edge, thus permitting the free use of both hands for holding or manipulating the straight edge or doing other work.

Another object of the invention is the production of a device of this class which is instantly yet securely adjustable.

Furthermore, the invention has for a purpose the production of a device which is simple and inexpensive in construction, yet thoroughly efficient and dependable in operation.

With these and other objects and advantages in view the invention, consisting in the construction, combination and novel arrangements or parts, will be clearly understood from the following description, reference being had to the accompanying drawing which forms a part of this application and in which like characters of reference indicate corresponding parts throughout the several views, of which,

Fig. 1 is a plan of a pair of the devices of my invention as applied to a level and straight edge.

Fig. 2 is a side elevation of the same.

Fig. 3 is an enlarged plan of the preferred embodiment of the invention.

Fig. 4 is a side elevation of the same.

Fig. 5 is an end elevation of the same.

Fig. 6 is a plan of a modification of the device.

Fig. 7 is a side elevation of the same, and

Fig. 8 is an end elevation of the same.

Referring, now, to the illustrations, 9 represents the stock of a mechanic's level resting upon a straight edge, 10. At opposite ends of the level stock I mount on the straight edge one of my devices, preferably including a metal bar, 11, the end portions of which are downwardly offset, as at 12, to rest upon and be secured to the straight edge as by screws, 13, thus leaving the intermediate portion of the bar spaced from the plane of the supporting end portions, 12.

The supporting portions, 12, of the bar are relatively narrower than the intermediate portion, and the end portion, 12, remote from the level is formed on opposite sides 60 with eyes, 14, which may be formed of strips secured on the sides of such portion, 12, whereby such portion is reduced in width as above mentioned. Through the said eyes is extended the web, 15, of a U-shaped spring wire, the arms, 16, of which extend along the opposite sides of the bars, 11, and their free end portions project a distance beyond the adjacent end of the bar, 11, and normally are sprung upwardly 70 from each other. The extreme free end portions of the said wires are bent inwardly toward each other, as at 17. Slidable on the intermediate or raised portion of the bar, 11, is a plate, 18, the end portions of which are bent, respectively, around the wires, 16, as at 19, and project below the edges of the bar. When it is desired to secure the level to the straight edge the former is placed in the position shown in Figs. 1 and 2 upon 80 the straight edge, and the plates, 18, slid in the direction of the level, thereby forcing the free end portions of the wires, 16, toward each other, causing the projecting parts, 17, to engage the end portions of the 85 level stock, or in openings, 20, in the said stock. Obviously, to detach the level from the straight edge it is only necessary to slide the plates, 18, from the level stock, thus causing the wires, 16 to spring outwardly and thus disengage the stock.

The modification presented in Figs. 6 to 8 comprises a bar, 21, formed with side flanges, 22. The web, 15, of the U-shaped spring wire is suitably engaged in a notch, 95 23, in the end of the bar, and the arms, 16, of the wire extend along the edges of the flanges, 22, and project from the end of the bar in the same manner as previously described. The sliding plate 18, may be identical with that presented in the preferred form, and is operated in the same manner.

Having thus described my invention, what I claim as new and desire to secure by Letters Patent of the United States, is,—

1. A clamp for removably securing a level stock to a straight-edge, including an elongated plate, having supporting means to be secured to the straight-edge and hold the plate spaced from the straight-edge, a U-shaped spring wire having its web disposed transversely of the plate, and its arms ex-

tended along the sides of the plate, the free end portions of the wire tending to spring outwardly from each other, and engageable, when forced toward each other, with the 5 level stock, and an element across the plate having grooves to freely receive the arms of the wire and the opposite sides of the plate, whereby the wire may be engaged and disengaged with and from the stock by accordingly 10 sliding said element toward and from the stock.

2. A clamp for removably securing a level stock to a straight-edge, including an elongated plate having offset end portions to be 15 secured to the straight-edge, a U-shaped spring wire having its web disposed transversely of the plate and its arms extended along the sides of the plate, the free end portions of the wire tending to spring from each other and engageable when forced 20 toward each other, with the level stock, and an element across the plate having grooves to freely receive the arms of the wire and the opposite sides of the plate, whereby the 25 wire may be engaged and disengaged with and from the stock by accordingly sliding said element toward and from the stock.

3. A clamp for removably securing a level stock to a straight-edge, including an elongated plate having reduced and offset 30 end portions to be secured to the straight-edge, a U-shaped spring wire having its web disposed transversely of the plate and its

arms extended along the sides of the plate, the free end portions of the wire tending to 35 spring from each other and engageable, when forced toward each other, with the level stock, and an element across the plate having grooves to freely receive the arms of the wire and the opposite sides of the 40 plate, whereby the wire may be engaged and disengaged with and from the stock by accordingly sliding said element toward and from the stock.

4. A clamp for removably securing a level stock to a straight-edge, including an elongated plate having offset end portions to be secured to the straight-edge, eyes formed on opposite sides of one of said end portions, a U-shaped wire having its web extended 50 through said eyes, and its arms extended along the sides of the plate, the free end portions of the arms being extended from the plate and having a tendency to spring from each other, and adapted when forced 55 toward each other to engage the level stock, and an element across the plate having grooves to freely receive the wire and the opposite sides of the plate, whereby the wire 60 may be engaged and disengaged with and from the stock by accordingly sliding said element toward and from the stock.

In testimony whereof I have hereunto set my hand this 28th day of April, 1922.

STEPHEN CONDON.
